FRANCIS KRICK, OF FIDELITY, OHIO, ASSIGNOR TO HIMSELF AND
ELI SINKS.

Letters Patent No. 84,285, dated November 24, 1868.

IMPROVEMENT IN LIFTING-JACK

The Schedule referred to in these Letters Patent and making part of the same.

To all whom it may concern:

Be it known that I, FRANCIS KRICK, of Fidelity, in the county of Miami, in the State of Ohio, have invented a new and improved Lifting-Jack; and I do hereby declare that the following is a full and exact description thereof, reference being had to the accompanying drawing, and the letters of reference marked thereon.

The nature of my invention consists in the arranging together two notched bars, one of which is moved by a lever, and to which is fastened a spring-catch to stay it, thus forming an improved lifting-jack.

To enable others skilled in the art to make and use my invention, I will proceed to describe its construction and operation.

The figure represents the lifting-jack.

B represents a notched bar, to the lower end of which is attached a convex base, H, and near the upper end are guides D, one on either side. These guides have projections, which pass within the grooves of the bar A. At the upper end of this bar a fulcrum is formed by the pin n, for the lever C, which has, for its position, a place between the ears of the bar.

To the upper end of the lever is attached a stirrup, K, which is held by the bolt m.

To the lower end of the bar A is attached the guide E by the bolt o, which also forms the fulcrum for the lever F. The spring-catch G is attached to the bar.

Operation.

By elevating the lever, the stirrup falls into the notches of the bar A; then by depressing the lever, this bar is elevated, and the spring-catch drops into successive notches as the bar is being elevated, and prevents a return of the bar. When it is desirable to let the bar down, the spring-catch is thrown out by the lever F.

What I claim as my invention, and desire to secure by Letters Patent, is—

The combination and arrangement of the bars A B, the lever C, stirrup K, guides E D, and spring-catch G, constructed substantially as and for the purpose specified.

FRANCIS KRICK.
